UNITED STATES PATENT OFFICE.

CHARLES WILLIAM GEORGE ALDRIDGE, OF LONDON, ENGLAND.

DESIGN FOR A GAME-BOARD.

SPECIFICATION forming part of Design No. 32,768, dated May 29, 1900.

Application filed March 20, 1900. Serial No. 9,456. Term of patent 7 years.

To all whom it may concern:

Be it known that I, CHARLES WILLIAM GEORGE ALDRIDGE, a subject of the Queen of Great Britain, residing at Teddington, London, in the county of Middlesex, England, have invented and produced a new and original Design for Game-Boards, of which the following is a specification, reference being had to the accompanying drawings, forming part thereof.

Referring to the drawings, Figure 1 is a plan view of a game-board embodying my new and original design, and Fig. 2 a section thereof upon the line 2 2.

As shown in the drawings, the leading or material feature of my new and original design comprises a rectangular body portion 3, in which are formed a plurality of cup-shaped recesses 4, arranged in series longitudinally and transversely thereof, and a

plurality of projecting pins 5, arranged also in longitudinal and transverse series to alternate with the longitudinal and transverse series of recesses 4. Arranged at one end of the body 3 is a curved spring 6, projecting longitudinally of the body 3.

Having fully described my invention, I claim as new and desire to secure by Letters Patent—

The design for a game-board, substantially as herein shown and described.

In testimony that I claim the foregoing as my invention I have signed my name, in presence of the subscribing witnesses, this 10th day of February, 1900.

CHARLES WILLIAM GEORGE ALDRIDGE.

Witnesses:

CLAUDE BERTRAM ELLIS,
EDITH MOORE HEATHERDOWN.
